(57) **CLAIM**

The ornamental design for a rack for dishwasher, as shown and described.

DESCRIPTION

FIG. 1 is a front perspective view of the rack for dishwasher showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a perspective view of the rack for dishwasher showing the state of use with sliding element pushed down; and,

FIG. 10 is a perspective view of the rack for dishwasher showing the state of use with the tines folded.

The broken lines depict portions of the rack for dishwasher that form no part of the claimed design. The dash-dot broken lines are to show enlargement and form no part of the claimed design.

1 Claim, 10 Drawing Sheets---
